ATTORNEY

UNITED STATES PATENT OFFICE.

DAVID L. VAUGHAN, OF RIVERTON, NEW JERSEY.

ANTICREEPER.

1,367,901.

Specification of Letters Patent.

Patented Feb. 8, 1921.

Application filed March 12, 1920. Serial No. 365,140.

To all whom it may concern:

Be it known that I, DAVID L. VAUGHAN, a citizen of the United States, residing at Riverton, in the county of Burlington and State 5 of New Jersey, have invented certain new and useful Improvements in Anticreepers, of which the following is a specification.

The object of my invention is to provide a novel, simple and efficient anticreeping device 10 for railroad rails wherein the device is formed of spring metal and is provided with spaced end bearing or rail gripping parts and an intermediate bearing or rail gripping part or parts, and wherein the device 15 is adapted to be sprung from its normal condition by parts of the railroad structure to engage the spaced and intermediate bearing parts of the device with a rail base and to cause the spaced end bearing parts to be held in gripping engagement with the rail base. 20

With the above and related objects in view, the invention consists of the elements and the combinations of them hereinafter described and claimed.

30 In the accompanying drawings, illustrating the invention,

Figure 1 is a top view of a part of a railroad structure provided with an anticreeping device embodying my invention.

35 Fig. 2 is an elevation of the parts shown in Fig. 1, showing the railroad rail in section.

Fig. 3 is a perspective view of the spring anti-creeping device.

40 Fig. 4 is a sectional detail on line 4—4 of Fig. 2.

Fig. 5 is a perspective view of a modified form of the spring anticreeping device.

Referring to the drawings, 2 designates 45 a portion of a railroad cross tie, 3 a tie plate thereon and 4 a portion of a railroad rail supported upon the tie plate.

The tie plate 3 is provided with a rib 5 which is engaged by one side of the rail base 6 and prevents lateral displacement of the rail 4 by the thrust of wheel flanges against the opposite side thereof.

50 The rail 4 and tie plate 3 are held down upon the cross tie 2 by the usual spikes 7 and 8 which are driven through holes 9 and 10, respectively, in the plate 3 and into the cross

tie 2, and the heads of which engage the top of the rail base 6. The plate 3 is also provided with a spike hole 11 to receive a spike similar to the spike 8 to perform the same function performed thereby. The spike 7 assists the rib 5 in preventing lateral displacement of the rail 4 in one direction, and the spike 8, together with a similar spike driven through the hole 11 and into the cross tie 2, prevents lateral displacement of the rail 4 in the opposite direction.

The parts thus far described and the functions which they perform are well known in this art and no detailed description thereof 70 is deemed necessary herein.

My improved anticreeping device 12 is associated with the parts previously described and by coöperation therewith prevents the rail 4 from creeping under the well 75 known conditions which cause such action.

The anticreeping device 12 is formed of spring metal, one 12^a being adapted to be interposed between the spike 8 and the adjacent edge of the rail base 6, and another 80 12^b being adapted to be interposed between the rail base 6 and a spike driven through the hole 11 and into the cross tie 2.

The end portions 13 of the device 12 are made wider than the central portion 14 85 thereof, the device gradually widening from its central portion 14 to its end portions 13 to provide oppositely-directed, wedge-like end portions, as clearly shown in the drawings, for a purpose hereinafter 90 explained.

One side of the device 12 is provided with a row of teeth 15 which extends from end to end thereof, and in the normal condition of the device, as shown in Fig. 3, and at 12^a in 95 Fig. 1, the central teeth 15 of the row are back of a straight line which extends between the end teeth 15 of the row. In other words, when the device, in its normal condition, is placed against the edge of one side 100 of the rail base 6 with the end teeth 15 of the row against the rail base edge, the central teeth 15 of the row will be back or spaced from the edge, as shown at 12^b in Fig. 1; and the rail base edge may thus represent the straight line above referred to.

In applying the anticreeping device to a rail, the device is placed upon the tie plate 3 with the end teeth 15 of the row thereof against the rail base edge and with the central portion of the device over a part of a spike hole in the plate, as shown at 12^b in

Fig. 1. A spike, such as the spike 8, is then driven through the hole and into the cross tie against the outer face of the anticerping device and the opposing wall of the spike 5 hole. This operation will cause the spike to spring the device from its normal condition by pressing the central portion thereof toward the rail base until the device assumes the condition shown in Fig. 4 and at 12^a in 10 Fig. 1, wherein the central teeth 15 of the row are forced into gripping engagement with the rail base 6 by the direct pressure of the spike, and the outer or end teeth 15 are forced into gripping engagement with the 15 rail base by the spring action of the device in tending to resume its normal condition.

When the device is thus applied, the teeth 15 thereof embed themselves in the rail base edge, as illustrated, and the wide or wedge-like end portions 13 extend beyond the sides of the spike, so that any tendency of the rail to creep will tend to draw one of the wedge-like end portions 13 between the spike and the rail base and thus prevent the rail from 25 creeping relatively to the tie plate 3 and the cross tie 2 which constitute stationary parts of the road bed supporting the rail 4.

The anticerping device is held against vertical displacement relatively to the rail 30 base by and between the head of the spike engaged therewith and the underlying tie plate.

In Fig. 5 I have shown a modification wherein the anticerping device 12 is provided with two end bearing teeth 16 and one intermediate or central tooth 17 in lieu of the row of teeth 15 shown in Fig. 3. In all other respects the device shown in Fig. 5 is like the device shown in Fig. 3.

40 I claim as my invention:—

1. The combination with a railroad rail and a stationary part of a road bed supporting the rail, of an anticerping device formed of spring metal and having two spaced bearing parts and an intermediate bearing part 45 back of a straight line drawn between said spaced parts in the normal condition of said device, and means on said stationary part holding said device sprung from its normal 50 condition with its three bearing parts engaged with the base of said rail.

2. The combination with a railroad rail and a stationary part of a road bed supporting the rail, of an anticerping device formed 55 of spring metal and having two spaced bear-

ing parts and an intermediate bearing part back of a straight line drawn between said spaced parts in the normal condition of said device, and means on said stationary part holding said device sprung from its normal 60 condition with its three bearing parts engaged with the base of said rail, said device having a wedge shaped portion adapted to prevent the movement of the device between the rail base and said means when the rail 65 tends to creep.

3. The combination with a railroad rail and a stationary part of a road bed supporting the rail, of an anticerping device formed of spring metal and having a row of bearing teeth on one side thereof, the intermediate teeth of the row being back of a straight line drawn between the end teeth of the row in the normal condition of said device, and means on said stationary part holding said 70 device sprung from its normal condition with all the teeth of said row engaged with the base of said rail.

4. The combination with a railroad rail and a stationary part of a road bed supporting the rail, of an anticerping device formed of spring metal and having a row of bearing teeth on one side thereof, the intermediate teeth of the row being back of a straight line drawn between the end teeth of the row in 80 the normal condition of said device, and means on said stationary part holding said device sprung from its normal condition with all the teeth of said row engaged with the base of said rail, said device having a wedge 85 shaped portion adapted to prevent the movement of the device between the rail base and said means when the rail tends to creep.

5. An anticerping device formed of spring metal and having end portions wider 90 than the central portion thereof and having a row of bearing teeth on one side thereof, the intermediate teeth of the row being back of a straight line drawn between the end teeth of the row, and said device being adapted 100 to be sprung from its normal condition to cause all the teeth of the row to engage a rail base and to cause the end teeth of the row to press against the rail base by the tendency of the device to resume its normal 105 condition.

In testimony whereof I affix my signature hereto.

DAVID L. VAUGHAN.
